(57) **CLAIM**

The ornamental design for a livestock feeder, as shown and described.

DESCRIPTION

FIG. 1 is a front perspective view of the livestock feeder showing our design, in an assembled condition; FIG. 2 is a front elevation view thereof, the left, right and rear elevation views are mirror images.

FIG. 3 is a top plan view thereof;

FIG. 4 is a bottom plan view thereof.

FIG. 5 is an exploded front perspective view of FIG. 1.

FIG. 6 is an exploded front elevation view thereof; the left, right and rear elevation views are mirror images.

FIG. 7 is a perspective view of the base of FIG. 1, shown separate for clarity of illustration.

FIG. 8 is a front elevation view thereof; the left, right, and rear elevation views are mirror images.

FIG. 9 is a top plan view thereof.

FIG. 10 is a bottom plan view thereof.

FIG. 11 is a perspective view of the hopper of FIG. 1, shown separately for clarity of illustration.

FIG. 12 is a front elevation view thereof; the left, right, and rear elevation views are mirror images.

FIG. 13 is a top plan view thereof;

FIG. 14 is a bottom plan view thereof.

FIG. 15 is a perspective view of the lid of FIG. 1.

FIG. 16 is a front elevation view thereof; the left, right, and rear elevation views are mirror images.

FIG. 17 is a top plan view thereof; and,

FIG. 18 is a bottom plan view thereof.

The broken lines illustrate portions of the livestock feeder that form no part of the claimed design.

1 Claim, 18 Drawing Sheets
